UNITED STATES PATENT OFFICE.

EDWIN HART PRATT, OF CORVALLIS, OREGON.

UNIT TRAY.

Application filed June 20, 1924. Serial No. 721,256.

To all whom it may concern:

Be it known that I, EDWIN HART PRATT, a citizen of the United States, and a resident of Corvallis, in the county of Benton and State of Oregon, have invented certain new and useful Improvements in Unit Trays, of which the following is a specification.

This invention relates to tray units and has for its object the provision of a tray having slidable handles adapted to lock with legs of a superimposed tray so that it is possible to lock a plurality of trays in a vertical series.

A further object of the invention is the provision of readily removable hinges for connecting a pair of trays together or for hingedly connecting an inverted tray to the topmost tray of a series whereby the first mentioned inverted tray will form a cover for the series of trays.

A still further object of the invention is the provision of a receptacle forming a complete and independent unit in itself, and so constructed that a series of the trays may be readily locked into a vertical column to form a chest, cabinet or trunk of any desired depth and capacity.

This invention will be best understood from a consideration of the following detailed description, in view of the accompanying drawing forming a part of the specification; nevertheless it is to be understood that the invention is not confined to the disclosure, being susceptible of such changes and modifications which shall define no material departure from the salient features of the invention as expressed in the appended claims.

In the drawings:

Figure 1 is a view in perspective of one end of the frame with parts broken away to show the slidable construction of the handle.

Figure 2 is a vertical section of a series of vertically disposed trays locked together.

Figure 3 is a fragmentary plan view partly in section showing the slidable construction of the handles.

Figure 4 is a fragmentary vertical section showing the guide for the slidable handle.

Figure 5 is a fragmentary view showing the pivotal connections of a pair of trays.

Figure 6 is a view in perspective of a guide for the sliding handles.

Referring more particularly to the drawings, it will be seen that the trays are formed substantially rectangular in shape and have

end bars 1 and longitudinal side bars 2 morticed or connected in any approved manner at their abutting ends. A bottom 3 is removably mounted in each frame in a manner which will be presently explained. The top face 4 of each end bar is cut away intermediate its ends to receive a metal plate 5. The bars are further cut away to provide a recess for the U-shaped guides 6 for the sliding arms 7 of a handle 8. The handles 8 are cut away as shown at 8^a to receive a strap for securing a plurality of the trays together. The inner vertical edge of the U-shaped guides 6 are cut away as shown at 7^a which is adapted to receive the projection 10 on the inner adjacent edges of the sliding arms 7 of said handle.

The upper ends of the U-shaped guides 6 are provided with up-standing lugs 11 which 7^b are adapted to be passed through perforations in the plate 5 and swaged over for locking said plate to the upper edges of the U-shaped guides 6. Secured within a cut-out portion of the under face of the bottoms 8^b of the end bars 1 of the frame are plates 12^a which extend inwardly of the end bars. U-shaped legs 12 are secured to the inward extensions of said plates and are adapted to support the trays above the top of a table. 8^c The legs are positioned to receive the inner ends of the arms 7 of the handle 8 when the trays are superimposed upon each other with the U-shaped legs projecting into the underneath tray. The legs 12 are so positioned 9^d that they will align with the inner ends of the guides 6 so that when the handle 8 is shoved inwardly the arms 7 of the handle will be inserted into the U-shaped legs 12 and whereby a series of trays may be locked 9^e in rigid relation and in vertical alinement. The extensions of the plate 12^a rest against the under faces of each bottom.

The bottoms 3 are removable and if desired they may be dispensed with and the frames locked together in the manner which has just been described for forming a trunk or chest as shown more particularly in Figure 3. As disclosed in Figures 2 and 4, the bottoms 3 of each tray rest on the projecting plates 12^a which are secured to the under face of each end bar 1. Therefore it is only necessary to reach beneath each frame and raise the bottom from its support on the plates 12^a for removing the bottoms since the arms 7 may be moved to their outermost position to permit such removal.

A closure for the trunk, chest or a single tray may be provided by hinging one of the trays to a side bar 2 of the frame of the tray whereby said tray is swingably mounted from a side edge of the lower tray and adapted to be positioned in an inverted manner on top of the tray. Provision is made for such a situation by forming horizontal slots 13 in the side members and at a predetermined distance from the top edges of the trays which are adapted to receive the corrugated angularly disposed sections 14 of the hinged members 15 which are pivoted together at 16. The hinges are readily removable and due to the corrugations of the plates 14 they will provide sufficient frictional resistance to displacement to maintain the hinges in position. The tray forming the closure for a series of trays may be readily removed when desired. The bottoms 3 may be removed from the intermediate frames of the trays so that the trays may form a chest or trunk of considerable depth.

When it is desired to release the trays it is only necessary to withdraw the handle 8 whereby the arms 7 will be moved from their locking engagement with the legs 12 of the trays.

The notches 8^a of the handles provide a series of vertically alined recesses to receive a strap for securing in a more rigid manner the combined trays which are coordinated to form a trunk or chest.

What I claim is:

1. A tray comprising a frame having pairs of spaced end bars and side bars, a bottom mounted in the frame, guides mounted in the end bars, handles having inwardly projecting arms slidably in the guides, means to prevent complete withdrawal of the arms of the handles from the guides and U-shaped legs secured to the under face of the end bar and in vertical alinement with the guides whereby when a second tray is superimposed upon another tray and the legs are disposed within the lower tray the arms of the handles may be moved into the alined legs for locking the trays together.

2. A tray comprising a frame having end bars and side bars, and a bottom removably mounted in the frame, handles having pairs of arms slidably mounted in the end bars with the arms movable into the trays, legs secured to the bottom of the tray and alining

with the slidable arms and adapted to receive the arms of a second tray when the first mentioned tray is superimposed upon the second tray whereby the trays are locked rigidly together.

3. A tray comprising a frame having end bars and side bars, a bottom mounted in the frames, said end bars being provided with spaced recesses, a plate having U-shaped guides secured thereto in spaced relation and depending from said plate and adapted to be received within the recesses in the end bars, U-shaped handles having arms slidably mounted in the guides with the inner free ends of the arms movable into the tray, said trays being provided with U-shaped legs for supporting the tray and secured to the bottom of the tray and in a lateral alinement with the inner ends of the guides, said legs of a superimposed tray being adapted to aline with the guides for receiving the movable arms of the handles whereby the trays are locked in rigid relation with each other.

4. A tray comprising a frame having end bars and side bars, handles slidably mounted in the end bars, means secured to the bottom of the tray and adapted to cooperate with the slidable handles of a tray positioned below the superimposed tray for locking said trays together.

5. A tray comprising a frame having end bars and side bars, handles slidably mounted in the end bars, means secured to the bottom of the tray and adapted to cooperate with the slidable handles of a tray positioned below the superimposed tray for locking said trays together, and a removable cover adapted to be connected with one of the trays.

6. A tray comprising a frame having end bars and side bars, handles slidably mounted in the end bars, U-shaped members secured to the under face of each end bar and extending inwardly of each end bar and adapted to receive the slidable handles of a tray positioned below the superimposed tray for locking the trays together, bottoms removably mounted in each tray and adapted to be supported at the ends thereof by the U-shaped members, and a removable cover adapted to be connected with one of the trays.

EDWIN HARP PRATT.
